J. F. G'SELL

APPARATUS FOR MAKING SPRING HEEL SHOE SOLES

Original Filed July 16, 1923

Inventor:
Julius F. G. Sell,
Ripley, King Island.
His Attorneys.

UNITED STATES PATENT OFFICE.

JULIUS F. G'SELL, OF JERSEYVILLE, ILLINOIS, ASSIGNOR, BY MESNE ASSIGNMENTS, TO INTERNATIONAL SHOE COMPANY, OF ST. LOUIS, MISSOURI, A CORPORATION OF DELAWARE.

APPARATUS FOR MAKING SPRING-HEEL SHOE SOLES.

Original application filed July 16, 1923, Serial No. 651,733. Divided and this application filed May 14, 1924. Serial No. 713,334.

To all whom it may concern:

Be it known that I, JULIUS F. G'SELL, a citizen of the United States, residing at Jerseyville, county of Jersey, State of Illinois, have invented a new and useful Apparatus for Making Spring-Heel Shoe Soles, of which the following is a specification.

This invention relates to an apparatus for making spring heel shoe soles, and consists in the novel construction hereinafter disclosed.

This application is a division of application Serial No. 651,733, filed July 16, 1923.

An object of the invention is to provide an apparatus wherein the shoe sole blank is molded to give it proper shape and at the same time to center and apply the heel lift throughout its entire area, including the inclined beveled wall at the forward end of the lift.

Additional advantages of the invention will be apparent from the following detailed description thereof, taken in connection with the accompanying drawing, in which

Fig. 1 is a top plan view of the apparatus.

Fig. 2 is a side elevation thereof.

Fig. 3 is a bottom plan view of the top section of the mold.

Fig. 4 is a top plan view of the bottom section of the mold.

Fig. 5 is a vertical section through the same.

Fig. 6 is a cross section taken on the line 6-6 of Fig. 1.

Fig. 7 is a cross section taken on the line 7-7 of Fig. 1.

As illustrated in the drawings the apparatus comprises a mold including a bottom section 1 preferably made of wood. In the upper face of this bottom section of the mold there are formed two cavities extending inwardly from each end of the mold. The inner portion of each of these cavities is formed with a flat wall 2 for supporting the upper face of the heel lift when the shoe sole is inserted therein in inverted position. The side walls 3 of the inner ends of the cavities conform generally to the curvature of the edges of the heel section of the soles and the heel lifts applied thereto. These

side walls have a downwardly extending section 4 in the plane with the plane of the inclined wall forming the line at the forward portion of the heel section of the sole. The front portion of each of the cavities is formed with an arch section 5 to support and form the concave portion of the shoe sole forward of the forward end of the heel lift. At the side edges of the arch section of the cavity are walls 6 that are substantially on a plane with the forward edge of the walls 4 and also substantially on a plane with the top of the arched portion 5 of the cavity.

Intermediate of the inner edges of the cavities formed in the base section is a transverse channel 7 at the center of which is formed a cylindrical opening 8. On the bottom wall of the base section and surrounding the opening of the cavity 8 is a retaining plate 9 held in place by suitable retaining means, such as wood screws 10.

Seated in the cavity formed by the opening 8 is a post comprising a circular base section 11 to which is connected a stud 12 preferably rectangular in cross section. The stud 12 has ratchet teeth formed on one edge and the post is positioned in the cavity formed by the opening 8 in such a manner that the base section thereof seats on the upper wall of the retaining plate 9, the stud 12 extending vertically above the upper plane of the base of the mold with ratchet teeth facing outwardly toward one side edge of the mold. A retaining plate 13 having an opening 14 therein is secured in position in the channel 7, with the stud 12 projecting through said opening 14. A cotter pin 14a may be mounted in an opening in the stud above the plate 13 for retaining the post in position when the plate 9 is removed. An expansion spring 15 is mounted in the cavity 8 and bears against the base section 11 of the post at one end and against the under face of the retaining plate 13 at the other end, so as to resiliently support the post in position in the cavity. The post constitutes one element of a latch device for holding the two mold sections together.

Dowel pins 16 project upwardly from the

base section of the mold for centering the upper section thereof when the same is placed in position.

The upper section of the mold has its under face formed to conform in general contour with the bottom of the shoe sole with the heel lift applied thereto, there being provided a flat wall 17 and a flat wall 18 fitting over the heel area of the shoe sole and inclined sections 19 and 20 arranged to form the downwardly deflected line forward of the heel section of the sole, and the concave portions 21 and 22 forming the arched portion of the sole. Intermediate of the walls 17 and 18 is a centrally disposed opening 23 into which the upper end of the post extends. There is also formed in the upper section of the mold dowel pin openings 24 that cooperate with the dowel pins 16 in centering the two sections of the mold.

A latch bolt housing 25 is secured to the inner face of the upper mold section adjacent to the opening 23, and a latch bolt 26 is mounted in said housing in such a manner that it projects across the opening 23, said latch bolt having its projecting edge formed with ratchet teeth adapted to cooperate with the ratchet teeth of the post to latch the two mold sections together. The latch bolt is provided with a push rod 27, said push rod extending outwardly beyond the edge of the mold section. A spring 28 attached at one end to the push rod and at the opposite end to the wall of the mold section normally tends to move the latch bolt inwardly into engagement with the stud of the post. To release the latch pressure is exerted on the push rod 27, unlocking the latch device.

The operation of the apparatus is as follows. The heel lifts are inserted in reverse position in each end of the bottom mold section after a quantity of glue or cement has been applied over the area thereof, it being understood, however, that the glue or cement may be applied to the inner face of the heel lift before the same is inserted in the mold cavity. A flat sole is then placed in each of the cavities of the bottom mold section in such manner that the heel section is centered upon the heel lift. The top mold section is then centered upon the base section of the mold and pressed downwardly, being retained in position by the latch device. The molds are so constructed that a plurality of the same, after having been filled with the soles in the manner described, may be put in a press of any suitable type and pressure applied to the molds, thus clamping each pair of mold sections tightly together. This forms a complete sole and exerts sufficient pressure to cause the heel lift to adhere uniformly throughout its entire area, including a tight connection along the beveled edge of the heel lift with a contiguous area of the heel section of the shoe,

After forming and adhering operation has been completed in the press pressure is released and the molds removed from the press, the two sections of the mold released from each other and the completed shoe soles removed from the molds.

I am aware that the invention may be modified in certain particulars without departure from the spirit and scope thereof. I do not limit myself unessentially, but what I claim and desire to secure by Letters Patent is:—

1. An apparatus for making spring heel soles, which consists in a base mold section having a shape-forming cavity therein, a top section adapted to be applied to said base section and cooperate therewith to shape a sole blank, a latch element in the base section comprising a ratchet, and a releasable lock bolt supported by the top section and adapted to cooperate with said ratchet to prevent separation of the two sections of the mold when latched.

2. An apparatus for making spring heel soles, which consists in a base mold section having a pair of cavities extending inwardly from each end thereof, said cavities having a flat wall and a side wall conforming generally to the contour of the heel section of a sole blank, a downwardly deflected extension of the side wall for forming a spring heel line forward of the heel section, a top mold section adapted to fit over the base section, a latch device for holding the two sections in latched position, and an element for releasing the latch device.

3. An apparatus for making spring heel soles, which consists in a base mold section having a pair of cavities extending inwardly from each end thereof, said cavities having a flat wall and a side wall conforming generally to the contour of the heel section of a sole blank, a downwardly deflected extension of the side wall for forming a spring heel line forward of the heel section, a top mold section adapted to fit over the base section, a latch device for holding the two sections in latched position, an element for releasing the latch device, and centering means for centering the two elements of the mold.

4. An apparatus for forming spring heel soles, comprising a base section having a pair of shaping cavities therein, a top section adapted to be applied to said base section and to cooperate therewith to shape a sole blank, a resiliently supported latch element in the base section, and a releasable lock bolt supported by the top section adapted to clamp the two elements together, said latch device and lock bolt being arranged to permit movement of the mold sections under pressure toward each other while retaining the sections against separating movement.

5. A mold for forming a sole blank and for bonding the heel lift thereto, comprising a base section having a heel lift receiving portion, a spring line forming portion and an arch forming portion, and a top section adapted to be received upon the base section for clamping the heel lift and heel

portion of a sole blank together, and adapted to move downwardly under pressure to shape the sole blank and to exert pressure upon the heel area of the sole blank effectively to bond the heel lift to the heel portion of the sole blank. 10

JULIUS F. G'SELL.
